Philip, New Haven & Fish

UNITED STATES PATENT OFFICE.

FRED ASHWORTH, OF BEVERLY, MASSACHUSETTS, ASSIGNOR, BY MEANS ASSIGNMENTS, TO UNITED SHOE MACHINERY CORPORATION, OF PATERSON, NEW JERSEY, A CORPORATION OF NEW JERSEY.

GUARD FOR SHOE-STITCHING MACHINES.

1,253,331.

Specification of Letters Patent. Patented Jan. 15, 1918.

Application filed December 29, 1915. Serial No. 69,228.

To all whom it may concern:

Be it known that I, FRED ASHWORTH, a citizen of the United States, residing at Beverly, in the county of Essex and State of Massachusetts, have invented certain new and useful Improvements in Guards for Shoe-Stitching Machines; and I do hereby declare the following to be a full, clear, and exact description of the invention such as will enable others skilled in the art to which it appertains to make and use the same.

This invention relates to guards for shoe stitching machines.

In a common type of a curved needle lock stitch shoe sewing machine the shoe upper comes in close proximity to the field of operation of the looper and take up during the stitching operation. The looper and take up carry a wax thread, and are often coated with oil, so that if the upper comes in contact with them it will be damaged. To keep the wax in fluid condition the looper and take up are heated, and any contact with one of these heated parts will often discolor certain kinds of shoe uppers.

The primary object of the present invention is to provide a guard of improved construction to hold the shoe upper out of the field of operation of the looper and take up.

In accordance with this object, one feature of the invention contemplates the provision of a guard for the shoe stitching mechanism comprising a holder attached to the machine between the take up and the work, and an apron adjustably mounted on the holder and located between the looper and the work. The apron can be adjusted longitudinally of the holder to a predetermined position with reference to the work support, and locked in this position.

In the preferred form of the invention the guard is made of thin sheet metal to give sufficient rigidity, and still afford sufficient space in front of the stitch forming mechanism for the movement of the upper. It is often necessary to have access to the looper for retreading, inspecting, etc., and heretofore the apron has been constructed of leather to give access to the looper. Leather, however, is not sufficiently rigid and durable to form an efficient guard. Accordingly another feature of the invention contemplates the provision of a thin metal guard for a shoe stitching machine to pro-

tect the shoe upper from the stitch forming mechanism, the guard being pivotally mounted on the machine so that it can be readily swung out of operative position to give access to the looper.

The invention also includes certain other features of construction and combinations of parts which are hereinafter described and set forth in the claims.

The various features of the invention are illustrated in the accompanying drawings in which Figure 1 is a front elevation of portions of a lock stitch sewing machine adjacent the sewing point, showing the relation of the improved guard thereto; Fig. 2 is a side elevation of the parts shown in Fig. 1; Fig. 3 is a detail sectional view showing the pivotal mounting of the guard upon the machine; and Fig. 4 is a detail view of the guard showing the adjustable connection of the apron with the holder.

The invention is illustrated as embodied in a shoe stitching machine of the type commonly known as the Goodyear rapid lock stitch. This machine is provided with the usual hook needle 10, looper 12, work support 14, presser foot 16, edge gage 18, take up 20, and auxiliary take up 22. These parts are substantially the same as those shown in the patent to French and Meyer, No. 473,870, dated April 26, 1892, to which reference is made for a detailed description of the parts.

The guard for protecting the upper from the stitch forming mechanism comprises a holder which is mounted on the machine in front of the take up, and an apron adjustably mounted on the holder in front of the looper. These parts are made of thin sheet metal which are properly shaped to extend closely to the path of movement of the take up and looper, so that sufficient room will be given for the movement of the upper during the stitching operation, and still affording sufficient rigidity to support the upper. The guard consists of a holder 24 and an apron 26 longitudinally adjustably mounted thereon. The holder 24 has an arm 28 by which the guard may be attached to the edge gage slide 30 to hold it in position. The apron 26 should be adjusted to a predetermined position with relation to the work support 14, and since a large number of different types of work supports are employed

on the stitching machine, the position of the apron may vary with different supports. The adjustable mounting of the apron upon the holder consists of a pair of slots 32 in 6 the bottom of the apron which fit over a pair of screws 34 mounted in the holder 24. To lock the apron in adjusted position the screws 34 are threaded into a clip 36 held on the back of the apron so that the apron is 10 clamped between the holder and the clip.

To adapt the guard to be swung out of operative position to give access to the looper and take up, the arm 28 on the holder 24 is provided with a slot 38 which fits over a 15 pivot screw 40. The slot 38 has a counter sunk opening 42 at its inner end, and the head of the screw 40 is shaped to fit within this counter sunk opening. By this construction the screw can be placed in the 20 counter sunk opening tight enough to hold the guard in place and still permit the guard to be rotated out of operative position to give access to the looper. When the head of the screw 40 is in the counter sunk opening 25 the guard may be pivotally rotatable, but cannot be displaced from the screw. The slot 38 affords a means by which the guard may be readily removed from the machine by withdrawing the screw from the counter 30 sunk opening 42. The operative position of the guard is determined by an abutment shoulder 44 striking against the slide 30. It will be noted that the pivotal mounting 35 of the guard is on its leading side with reference to the movement of the shoe upper, so that the feeding movement of the shoe tends to hold the shoulder 44 against the slide 30 and maintain the guard in correct operative position.

40 While the invention has been illustrated as embodied in a particular type of sewing machine, it is not limited to use in this type of machine, but may be employed in any type of machine in which the upper moves 45 in close proximity to the stitch forming mechanism, to protect the upper from injury.

Having thus described a preferred form of the invention, what is claimed as new is:

60 1. A guard for a shoe stitching machine comprising, a holder secured to the machine below the stitching point, a longitudinally adjustable apron attached to the holder and located in front of the looper, and means to 65 lock the apron in adjusted position.

2. A shoe stitching machine having, in combination, stitch forming devices including a looper and take-up, a guard for the work comprising a holder secured to the machine between the take-up and the work, 60 and an apron adjustably mounted on the holder between the looper and the work, the adjustable mounting of the apron consisting of a slot in the apron and a screw passing through the holder and said slot and secured 65 in a clip positioned behind the apron.

3. A guard for a shoe stitching machine comprising, a holder positioned adjacent the looper, and a thin metal apron on said holder positioned in front of the looper, said guard 70 having a pivotal mounting on the machine to be swung out of operative position to give access to the looper, said pivotal mounting consisting of a slotted arm projecting from the guard, said slot having an interlocking 75 connection with a screw in the machine which will permit a rotative movement of the guard while retaining it from removal from the screw.

4. A shoe stitching machine having, in 80 combination, stitch forming devices including a looper and take-up, a guard for the work comprising a holder positioned between the take-up and the work, and an apron on said holder positioned between the looper 85 and the work, said guard being pivotally mounted to be swung out of position to give access to the looper, the mounting including a slotted arm projecting from the guard, a counter-sunk opening in the slot, and a 90 pivot screw having a head to fit the counter-sunk opening of the slot, secured in the machine.

5. A shoe stitching machine having, in combination, stitch forming devices including a looper and take-up, a guard for the work comprising a holder positioned between the take-up and the work, and an apron on said holder positioned between the looper and the work, said guard being pivotally mounted to be swung out of position to give access to the looper, the mounting including a slotted arm projecting from the guard, a counter-sunk opening in the slot, a pivot screw having a head to fit the counter-sunk opening of the slot, secured in the machine, and an abutment on the guard for engaging the machine to determine the operative position of the guard.

FRED ASHWORTH.
